UNITED STATES PATENT OFFICE.

NATHAN ALLEN GIBBONS, OF MARTINS FERRY, OHIO, ASSIGNOR TO WHITAKER-
GLESSNER COMPANY, OF WHEELING, WEST VIRGINIA, A CORPORATION OF
WEST VIRGINIA.

COLLAPSIBLE BOX.

1,422,692.

Specification of Letters Patent. Patented July 11, 1922.

Application filed July 11, 1921. Serial No. 483,777.

To all whom it may concern:

Be it known that I, NATHAN ALLEN GIBBONS, a citizen of the United States of America, and resident of Martins Ferry, county of Belmont, and State of Ohio, have invented certain new and useful Improvements in Collapsible Boxes, of which the following is a specification.

This invention relates broadly to collapsible boxes, and more particularly to a box of the type commonly used by retail grocers in the delivery of goods.

The primary object of the invention is to provide a convenient form of collapsible box or crate for the use of grocers and others in the delivery of packages and small articles.

A further object is to provide a box of the character mentioned which is composed almost wholly of sheet metal, which is extremely simple in construction, which is readily collapsible into a flat form in which it occupies a minimum of space, and which possesses a marked degree of durability in that it is capable of withstanding more than ordinarily rough usage.

With these and other objects in view, the invention resides in the features of construction which will hereinafter be fully described, reference being had to the accompanying drawings, in which—

Figure 1 is a top plan view of the invention;

Figure 2 is a longitudinal section on line 2—2, Fig. 1;

Figure 3 is an end elevation;

Figure 4 is a transverse section on line 4—4, Fig. 1;

Figure 5 is a lateral edge view of the invention in its collapsed form; and—

Figure 6 is a partial horizontal section on line 6—6, Fig. 3.

Referring to said drawings, 1 indicates each of two opposite heavy-wire frames of substantially rectangular form. Mounted upon the opposite side members 1^a of the opposite frames are the opposite ends of two parallel side walls or panels 2 formed of sheet metal, said panels being disposed outward of said frames and having their ends coiled inward, as shown at 3, into embracing relation to said frame members 1^a.

The upper horizontal member 1^b of each wire frame has its opposite end portions bent outward, as is best shown in Figs. 1, 2 and 5, so that said member lies slightly out-

ward of the vertical plane of the side members 1^a, and mounted upon said horizontal member is the upper end of a sheet-metal end panel 4, said panel being disposed inward of said frame and having its said end coiled outward into embracing relation to said member. The lower end and lateral edges of said end panel 4 are coiled outward about the horizontal and lateral members, respectively, of a U-shaped wire 5 which serves to reinforce said panel. Said end panels have a height materially greater than that of the side panels 2 and, consequently, extend a substantial distance below the lower edges of said side panels for forming feet upon which the box may rest, as shown in Figs. 2, 3 and 4.

The lower horizontal member 1^c of each wire frame also has its opposite ends bent outward, as is best shown in Fig. 6, so that it occupies a position outward with respect to the vertical plane of the side members 1^a, thus permitting the adjacent end panel 4 to occupy a position in which its lower end is disposed between the beads 3 of the side panels 2 in abutting relation to said horizontal member 1^c so that it is braced by the latter against outward movement. To prevent inward swinging movement of the panel 4, a short narrow tongue 6 is struck up from the metal of said panel at an intermediate point in the lower portion of the latter and is bent outward and coiled into embracing relation to an inwardly-offset intermediate portion 1^d of the frame member 1^c.

Said end panels may have hand holes, as 7, provided therein adjacent to their upper ends for facilitating handling of the box. In forming said hand holes, tongues of suitable dimensions are struck up from the metal of the panel and are bent outward, upward and inward to form a roll-like handle 8.

A flat sheet-metal bottom 9 has one of its lateral edges mounted upon a horizontal hinge wire 10 which is carried by one of the side panels 2 slightly above an inturned reinforcing roll 2^a formed at the lower edge of the latter. Said wire 10 is of less length than the panel 2 and is attached to the latter by directing its opposite ends outward through the panel and then turning said ends back into overlying relation to the outer surface of the panel, as shown at 10^a. Said bottom 9 has said wire 10 received by 110

- an embracing coil 9^a formed on the edge thereof, said coil being provided with cut-out portions or openings 11 through which the hooks 10^a are directed. The opposite 5 lateral edge of the bottom 9 is coiled under to form a reinforcing roll or bead 9^b, and similar rolls or beads 9^c are formed at the opposite ends of said bottom. In the open form of the box, the roll or bead 9^b rests in 10 overlying seated relation to the roll or bead 2^a of the panel 2 which is located opposite the hinge. In seated position, the bottom closely engages the last-mentioned side panel and the opposite end panels 4 and constitutes means whereby the walls of the box 15 are effectually braced, rendering said box perfectly rigid.

When the box is to be collapsed, the bottom 9 is first forced upward, turning on the 20 hinge wire 10, until it lies closely against the side panel 2 by which said wire is carried, as shown in dotted lines in Fig. 4, whereupon the side walls or panels 2 may be relatively moved or shifted either to the 25 right or left, with their coiled ends 3 rotating on the members 1^a of the wire frames 1, until the flatly collapsed form shown in Fig. 5 is assumed by the parts. Practically considered, the act either of collapsing or 30 of setting up the box involves the work of but an instant.

It will be particularly noted that the side members 1^a of the wire frames stand vertically; that the upper and lower horizontal 35 members 1^b and 1^c of said frame are in the same vertical planes, and that, consequently, the end panels 4, located inward of the inwardly offset portions 1^a of said members 1^c, are held disposed in inwardly inclined 40 positions, as is best shown in Fig. 2. This is an important feature of the present invention in that it provides for the mounting of the boxes in superposed, or stacked, relation with the projecting lower ends, or feet, of 45 the end panels received within the tops of underlying boxes and with the lower frame members 1^c seated directly over the upper frame members 1^b of such underlying boxes.

What is claimed is—

- 50 1. A collapsible sheet-metal box comprising wire frames of substantially rectangular form, side panels having their ends attached to the side members of said frames, end panels depending from the upper horizontal members of said frames and having their lower ends extending below the lower members of said frames to form feet, a bottom having hinge-like connection with the lower portion of one of said side panels, and means formed on the opposite side panel 55 for supporting the free lateral edges of said bottom.
- 60 2. A collapsible sheet-metal box comprising wire frames of substantially rectangular form, the upper horizontal member of each

frame being disposed outward with respect to the vertical plane in which said side members thereof are located, side panels having their ends attached to said vertical side members, end panels depending from said horizontal members and having their lower ends extending below the lower members of said frames to form feet, said end panels being disposed inward of and attached to said lower members, and a bottom hinged to 70 one of the side panels and foldable inward from seated parallel relation to the latter to a position at right angles thereto, and vice versa.

3. A collapsible sheet-metal box comprising 80 wire frames of substantially rectangular form, the upper horizontal member of each frame being disposed outward with respect to the vertical plane in which the side members thereof are located, side panels having their ends attached to said side members, end panels depending from said horizontal members and having their lower ends extending below the lower members of said frames to form feet, said end panels being disposed 85 inward of and attached to said lower members, a bottom having hinge-like connection with the lower portion of one of said side panels and foldable inward from seated parallel relation to the latter to extended horizontal position, and vice versa, and bottom supporting means provided on the opposite side panel.

4. A collapsible sheet-metal box comprising 100 wire frames of substantially rectangular form, the upper horizontal member of each frame being disposed outward with respect to the vertical plane in which the side members thereof are located, side panels having their ends attached to said side members, said panels having inwardly extending 105 reinforcing means provided at their lower edges, end panels attached to said horizontal members and having their lower ends extending below the level of the lower members of said frame to form feet, said end panels being inwardly inclined and disposed 110 inward of and attached to said lower members, and a bottom panel having hinge-like connection at one lateral edge with one of 115 said side panels and being foldable to and from seated parallel relation to the latter, said bottom panel when in extended position resting upon the reinforcing means of the opposite side panel.

5. A collapsible sheet-metal box comprising 120 wire frames of substantially rectangular form, the upper and lower horizontal members of said frames being disposed outward with respect to the vertical plane in 125 which said side members are located, side panels having their ends attached to said side members, said panels having inturned rolls or beads formed at their lower edges, end panels attached to said upper horizontal 130

members and having their lower ends extending below the level of the lower horizontal members of said frame, said end panels being disposed inward of and attached to said 5 lower members and being inwardly inclined, and a bottom panel having hinge-like connection with one of said side panels above the roll or bead of the latter and being foldable to and from seated parallel relation to the latter, said bottom panel when 10 in extended position being seated upon and supported by the roll or bead of the opposite side panel.

6. A collapsible sheet-metal box comprising 15 wire frames of substantially rectangular form, the upper and lower horizontal members of each frame being disposed outward of the plane in which the side members thereof are located, side panels having their end 20 attached to and adapted for rotary movement on said side members, end panels attached to the horizontal members of said frames and disposed inward with respect to the latter, the lower ends of said end panels 25 extending to a level below that of the lower frame member to form feet, and a bottom panel having hinge-like connection with one of said side panels and foldable to and from seated parallel relation to the latter, and 30 means carried by the opposite side panel for supporting the free lateral edge of said bottom panel when the latter occupies horizontal position.

7. A collapsible sheet-metal box comprising 35 wire frames of substantially rectangular form, the upper and lower horizontal members of each frame being disposed outward of the vertical plane in which the side members thereof are located, side panels having

their ends attached to and adapted for rotary movement on said side members, end panels suspended from the upper horizontal members of said frames and having their lower ends extending below the level of the lower members of said frames, said end 40 panels being inclined and disposed inward of said lower members, tongues struck up from said end panels and coiled into embracing relation to portions of said lower members, and a bottom having hinge-like connection with one of said side panels and adapted for folding movement to and from horizontal operative position.

8. A collapsible sheet-metal box comprising 45 wire frames of substantially rectangular form, the upper and lower horizontal members of each frame being disposed outward of the vertical plane of said side members and in a common vertical plane, side panels having 50 their ends attached to said side members, end panels suspended from the upper horizontal members of said frames and having their lower ends extending below the level of the lower members of said frames, said end panels inclined downwardly and inwardly and disposed inwardly of said lower members, means attaching said panels to said lower members, and a bottom having 55 hinge-like connection with one of said side panels and adapted for folding movement 60 to and from horizontal operative position.

In testimony whereof, I affix my signature in presence of two subscribing witnesses.
